US00D961505S

(12) **United States Design Patent** (10) Patent No.: **US D961,505 S**
(45) Date of Patent: **** Aug. 23, 2022**

(54) **BATTERY CHARGER**

- (71) Applicant: **Integra LifeSciences Corporation**,
Princeton, NJ (US)
- (72) Inventors: **Doug Birkholz**, Madison, WI (US);
Clay Mehnert, Madison, WI (US);
Brian Neeley, Cottage Grove, WI (US)
- (73) Assignee: **Integra Life Sciences Corporation**,
Princeton, NJ (US)

(**) Term: **15 Years**(21) Appl. No.: **29/825,544**(22) Filed: **Feb. 2, 2022****Related U.S. Application Data**

- (62) Division of application No. 29/665,628, filed on Oct. 5, 2018, now Pat. No. Des. 946,505.
- (51) **LOC (13) Cl.** **13-02**
- (52) **U.S. Cl.** **USPC D13/107**

CLAIM

The ornamental design for a battery charger, as shown and described.

DESCRIPTION

FIG. 1 is a perspective view of a battery charger showing our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the article that form no part of the claimed design.

1 Claim, 4 Drawing Sheets(56)
